WILLIAM JOHNSON, OF MILWAUKEE, WISCONSIN,

Letters Patent No. 90,550, dated May 25, 1869.

IMPROVEMENT IN CASK-WASHING MACHINES.

The Schedule referred to in these Letters Patent and making part of the same.

To all whom it may concern:

Be it known that I, WILLIAM JOHNSON, of the city and county of Milwaukee, and State of Wisconsin, have invented a new and useful Improvement in Cask-Washers; and I do hereby declare that the following is a full, clear, and exact description thereof, which will enable those skilled in the art to make and use the same, reference being had to the accompanying drawing, forming part of this specification, in which—

Figure 1 is a perspective view.

Figure 2, a longitudinal section.

Similar letters of reference in each of the figures indicate corresponding parts.

The object of my invention is to provide a machine for washing barrels and casks outside and inside.

A, the bed-frame.

B B B, standards for the slides.

C, pillow-block for the driving-shaft.

D, stationary cylinder.

E, hollow reciprocating cylinder-rod.

F, bevel-wheel on cylinder-rod E, with a feather in its eye, fitting into the groove in cylinder-rod E.

G, bevel-wheel on driving-shaft, gearing into wheel F.

H, driving-shaft, one end working into a rest on cylinder D, and the other supported by the pillow-block frame C.

I, fly-wheel.

K K, slides, working in the tops of standards B.

L L, cross-heads.

M, pitman.

O, keeper on the top of cylinder D.

P, keeper on the under side of cylinder D.

These keepers have a semicircle, fitting into a recess turned in the hub of wheel F, to hold it in gear.

Q Q, barrel or cask-holders, screwed on to the ends of cylinder-rod E.

R R, screws to hold the casks in place.

S S S S, springs in the holders, to steady the casks.

T, pipe to convey water to the cylinder D.

U, holes in cylinder-rod E, for the water to pass through, to be conveyed through cylinder-rod E to the bungs of the casks, and into them, for washing the inside.

V V, branch pipe.

W W, sprinklers, through which water is thrown to wash the outside of the casks.

X X, casks in the machine, to be washed.

Y, crank-pin.

Operation.

Put the casks in the machine as shown, the ends of the hollow cylinder-rod E fitting into the bungs of the casks. Turn on the water, and it will pass into the casks, and also will be forced through the sprinklers W W on to the outside of the casks.

The machine may be put into operation by a belt around a pulley on shaft H, or it may be operated by hand, by the crank-pin Y. As the shaft H is revolved, the casks are given a rotary motion, and a reciprocating at the same time, by the pitman M.

What I claim as my invention, and desire to secure by Letters Patent, is—

1. A barrel-washing machine, constructed with bed-frame A, standards B B B, cylinder D, cylinder-rod E, bevel-wheels F and G, driving-shaft H, slides K K, cross-heads L L, pitman M, and keepers O and P, substantially as described.

2. Cask-holder Q, screw R, springs S S, operated by cylinder-rod E, substantially as described.

3. Cylinder D, pipes T and V, sprinkler W, and holes U, in cylinder-rod E, for the purpose of supplying water, substantially as described.
